UNITED STATES PATENT OFFICE.

HORACE R. HAWKINS, OF AKRON, OHIO.

HAY-RACK FOR CARTS.

Specification of Letters Patent No. 29,075, dated July 10, 1860.

To all whom it may concern:

Be it known that I, HORACE R. HAWKINS, of Akron, in the county of Summit, in the State of Ohio, have invented a certain new and useful Improvement in Hay-Racks for Carts or Wagons; and I do hereby declare that the following is a full, clear, and exact description of the same, reference being had to the accompanying drawings, which form

10 a part of this specification, in which—

Figure 1 represents a top or plan view of my improved rack. Fig. 2 represents a side view of Fig. 1. Fig. 3 represents an end view, and Fig 4 represents an end view of 15 the rack folded up to be packed or stored away. A, A, represent a frame work which rests on the axle or axles of the cart or wagon to which it should be attached or fastened. The said frame work A, is provided with uprights a, a, a, a.

20 The rack is composed of bottom or base pieces D, D, arms B, B, and top pieces C, C. The arms B, B, are rigidly secured at their lower ends to the base pieces D, D, and are 25 also hinged together, as shown at F, in the drawings.

The top pieces C, C, are provided with eyes or staples e, and in this instance with crop pieces E, although it is not essential 30 that the crop pieces should be used; but they tend to strengthen the ends of the pieces C, and therefore when the rack is to be used for heavy work, it will be well to use them.

35 The operation is as follows: The upper ends of the arms B, B, are thrown apart until their shoulders b, b, rest upon the bottom pieces D, D, and then the rack is placed on the frame A, the uprights a, a, passing up between projections f, f, on the base 40 pieces D, D. The top pieces C, C, are now placed on the upper ends of the arms B, B—

their lower edges resting on shoulders c, c, while the staples or clasps are slipped over the ends of the arms B, B, as fully shown in the drawings.

45 If necessary a removable cross piece G, may be employed to keep the rack extended, the base pieces D, D, being provided with staples into which the piece G, can be slipped and there held by pins.

50 It will be seen that the space between the arms B, B, and pieces C, C, affords ample room for hay. When the rack is not in use, it can be removed from the wagon or cart and folded up so as to occupy but little 55 room, as fully shown in Fig. 4, of the drawings.

It is a great desideratum with farmers to have such implements and machines, as are simple, durable, and also capable of being 60 stored in as compact a manner as possible.

In the present invention I have contributed a good, firm, simple, and cheap article to the use of farmers; and what adds to its greater usefulness, is the fact, that it can be 65 quickly folded up and packed or stored away under cover, thus rendering it almost certain that the rack will not be left exposed to the weather as would be likely to be the case if it could not be so conveniently removed and folded up.

70 Having described my invention, what I claim as new and desire to secure by Letters Patent, is—

A removable folding hay rack for carts 75 or wagons, constructed and operating substantially as above set forth.

HORACE R. HAWKINS.
